Primary Examiner — John Windmuller*Assistant Examiner* — John R Yeh(74) *Attorney, Agent, or Firm* — Ladas & Parry LLP(57) **CLAIM**

We claim the ornamental design for a vacuum cleaner, as shown and described.

DESCRIPTION

FIG. 1 is a perspective view of a vacuum cleaner showing our new design.

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 of FIG. 1;

FIG. 9 is an enlarged view of the encircled portion 9 of FIG. 6; and,

FIG. 10 is an enlarged view of the encircled portion 10 of FIG. 7.

The broken lines in the figures represent portions of the vacuum cleaner that form no part of the claimed design.

1 Claim, 10 Drawing Sheets(56)
